GRINDING MACHINE

Albert Vuilleumier, Bristol, Conn., assignor, by
mesne assignments, to General Motors Corpora-
tion, Detroit, Mich., a corporation of Delaware

Application January 29, 1929, Serial No. 335,916

10 Claims. (Cl. 51—103)

This invention relates to grinding machines and comprises all the features of novelty herein disclosed in connection with a machine for feeding balls in a centerless grinding machine. An object of the invention is to provide improved mechanism for feeding balls especially to a centerless grinding machine having grooved wheels. Another object is to provide improvements in the mechanism of my copending application Serial 10 Number 226,005. To these ends and to improve generally and in detail upon machines of this character, the invention further resides in the various matters hereinafter described and claimed.

15 In its broader aspects the invention is not necessarily limited to the specific construction selected for illustrative purposes in the accompanying drawings in which

Fig. 1 is a side elevation of the machine with some parts omitted.

Fig. 2 is an end view with some parts in section and with some of the actuating mechanism omitted.

Fig. 3 is a similar view of the actuating mechanism with one set of cams omitted.

Fig. 4 is a perspective view of the work support.

Fig. 5 is a perspective view of the toggle mechanism.

Fig. 6 is a perspective view of a portion of one standard and associated mechanism.

Fig. 7 is a perspective view of a guide.

Fig. 8 is a perspective view of a bar.

Fig. 9 is a side view of one of the cam wheels.

Fig. 10 is a side view of another cam wheel.

35 Fig. 11 is an end view of parts shown in Fig. 2 to a larger scale.

Fig. 12 is a plan view partly in section of the feed block and associated mechanism.

Fig. 13 is a side view of the preceding.

40 Fig. 14 is a perspective view of certain details.

Fig. 15 is a perspective view of the feed plate.

The numeral 10 indicates a grinding wheel rotatable downwardly at the work at high speed and having peripheral ball grooves 12 (Fig. 12)

45 cooperating with similar ball grooves 14 on a regulating wheel 16 which has its axis tilted in a vertical plane substantially parallel to the axis of the grinding wheel. The regulating wheel rotates upwardly at the work and its inclination

50 causes the balls to constantly change their axes of rotation while resting on the inclined work support 18. The balls always occupy alternate grooves, first the odd grooves and then the even grooves, and a new ball is fed into the first groove

55 on every alternate advance of the loaded balls.

To permit this advance of the loaded balls along the work support past the ribs separating the ball grooves, the regulating wheel 16 is intermittently moved away from the grinding wheel by means of a slide and then moved back again. 60

The inclined work support is formed by the upper edge of a vertically adjustable plate 20 which has its sides grooved as indicated at 22 to allow close approach of the grooved abrasive wheels to the work support. The grooves in the

regulating wheel are progressively shallower in order to continue grinding as the balls get smaller. The plate 20 is slotted at 24 to permit its being clamped in vertically adjusted position by bolts 26. Vertical adjustment is effected by lifting 70

bars 28 secured to the plate and having inclined ends 30 engaging inclines 32 on a rod 34 guided endwise in a hole of the supporting casting 36. The rod is movable endwise by an adjusting screw 38 threaded in the supporting casting and having 75

a squared end 40 for a wrench. The supporting casting has a tongue 42 entering a slot in a lower slide 44 which carries the regulating wheel and is adjustable crosswise of the lower slide by a screw 46 threaded in the supporting casting and having 80

a collar 48 entering between a pair of forked uprights 50 on a bracket 52 attached to the lower slide. This adjustment places work support and feed mechanism in proper relation to the grinding grooves and the position is maintained by clamping bolts 54, which secure the supporting casting to the lower slide. 85

For advancing the balls from groove to groove, a feed plate or comb 60 is provided. This comprises a plate having lugs or teeth 62 which are spaced just twice as far apart as the ball grooves on the grinding wheels. The comb is carried by two spaced plates 64 bolted to lifting plates

66 which are slidable vertically in grooved ways 68 in a horizontal slide 70 and retained on the 90 ways by gib plates 72. The horizontal slide has upper and lower tongues 74 and 76 slidable in ways 78 on vertical standards 80 and retained in the ways by gib plates 82. Each standard 80 has an attaching lug 84 by which it is bolted to one side of the supporting casting and the standards are connected at the top by a top bar 86. The feed plate or comb 60 thus has provision for horizontal and vertical movement. Feed

movement of the comb comprises two intermittent horizontal steps, then a vertical lifting, then a horizontal retraction, and finally a vertical lowering to its original position. Assuming the first, second and third, etc. balls lying in the first, third, fifth, etc., ball grooves, the first feed 95

100

105

110

step advances all the balls to the second, fourth, sixth, etc. ball grooves. The next feed step advances all the balls to the third, fifth, seventh, etc. ball grooves while a new ball enters the first groove and a finished or last ball runs off the end of the work support. The feed comb is then lifted, retracted while above the balls, and lowered for feeding again.

Horizontal movement of the feed comb is effected as follows by reciprocation of the horizontal slide 70. A turnbuckle comprising an internally threaded housing 90, nuts 92, and threaded rods 94 and 96 has one rod 94 pivoted at 98 to the slide 70 and the other rod 96 pivoted at 100 in a fork of a bell crank lever 102 which is pivoted at 104 to a lug 106 on the front standard 80. An arm 108 of the bell crank lever carries a cam roll 110 engaging cam plates on a slotted cam carrying disc 112 whose hub 114 is keyed to a cam shaft 116 journaled in bushings in lugs 118 and 120 on a bracket 122 bolted to the lower slide 44. The cam shaft is an extension of a shaft (not shown) which controls the regulating wheel slide 44. The cam roll is shown ready for lifting by an incline 124 on an arcuate cam plate 126 bolted to the disc 112. This causes the first feed step of the comb. Later the cam roll rides up a second incline 128 on a second arcuate cam plate 130 and causes the second feed step. Still later the cam roll rides down a longer incline 132 and so allows the feed comb to be retracted by a spring 134 attached to the top bar 86 and to the slide 70. Arcuate plates 136 and 138 (Fig. 9), bolted to disc 112 in overlapping relation to the cam plates 126 and 130 complete the periphery of the cam.

Lifting, retraction, and lowering of the feed comb should occur only after the second feed step, in the illustrated construction, and the following mechanism is provided to effect it. The lifting plates 66 have their upper ends enlarged and slotted horizontally as at 140 to receive antifriction rolls 142 journaled on studs 144 and 146. Stud 144 has a collar 145 at one end and its other end is threaded in one end of a straight toggle lever 148 which is pivoted on a stud 150 of the top bar 86. Stud 146 is threaded in one end of a toggle lever 152 which is pivoted on a stud 154 of the top bar and the other end of toggle lever 152 is forked and offset to lie alongside of lever 148 between the arms of a bifurcated link 156. A pivot pin 158 passes through the arms of the link, through the end of lever 148 and through an antifriction roll 160 which is straddled by the forked end of lever 152. The upper end of link 156 is bifurcated and pivoted by a pin 162 to a long lever 164 pivoted on a stud 166 fixed to a lug 168 of the top bar. The lever 164 is pivoted by a pin 170 to a turnbuckle comprising a threaded casing 172, nuts 174 and threaded rods 176 and 178, the latter being pivoted by a pin 180 to a slide bar 182 which is slidably supported near its ends in ways 184 formed by slots and closure plates 186 at the ends of a yoke 188 whose hub 190 is bolted to the lug 118 of the bracket 122. The slide bar 182 is slotted at 192 to straddle the cam shaft. The slide bar carries two cam rollers 194 and 196 for actuation by arcuate cam plates 198 and 200 bolted at opposite sides of a slotted disc 202 whose hub is keyed to the cam shaft. The cam plates are so located and so shaped as to reciprocate the bar 182 to lift and lower the feed comb through the toggle connection in proper timed relation to the retracting movement of the feed comb.

Balls are fed onto the work support by the following mechanism. The balls travel by gravity in a stream through a pipe (not shown) to the upper end of an inclined feed tube 210 which is integral with a feed block 212 bolted to a shelf 80 on the supporting casting. The exit opening 214 extends through a finished face 216 on the feed block which fits closely up to one of the plates 64 on the feed comb and closely up to a thin shutter plate 218 which is lifted and lowered with the feed comb. The shutter plate has an attaching portion 220 which is fastened across a horizontal guide slot 222 on a vertically slideable block 224, the slot receiving and guiding a reduced extension 226 of the feed comb. The block has a tongue 228 to guide it vertically in a slot of a stop plate 230 fastened to the front standard 80. The shutter plate 218 and the plate 64 retain the balls in the feed tube while the feed comb is actuated but, when the first notch in the feed comb moves into alignment with the exit opening, the lowermost ball moves out into the notch and onto the work support and is prevented from passing too far by the stop plate 230 which extends up close to the end of the grinding wheel. The exit opening 214 communicates with a lateral slot 232 in the feed block so that, while the shutter plate retains the remaining balls in the feed block, the ball being fed along the work support will be free to move a little 135 way transversely down the incline of the work support to pass the first rib on the grinding wheel. The edge 234 of the feed block is inclined to accommodate the inclination of the regulating wheel and the work supporting plate is notched 110 at 236 to let the shutter plate overlap the work support, the overlapping portion retaining the balls when the shutter plate is raised. When the finished ball moves off the rear end of the work support, it runs down an inclined channel 238 115 in a block 240 fastened at one side of the rear standard 80. Part of the block is inclined at 242 to accommodate the inclination of the regulating wheel and the block also has a cut away portion at 244 to receive a corner of the work supporting plate 20.

Summarizing a cycle, the regulating wheel 16 being retracted from the grinding wheel 10, a new ball is fed forward by the feed plate one step and simultaneously the already loaded balls 125 in alternate grooves are all advanced to the next grooves. The regulating wheel is then returned and the balls are partly ground. The regulating wheel is again retracted and the feed plate advances another step to carry a new ball between 130 the wheels into the first groove and simultaneously all the loaded balls are again advanced to the next following grooves. The regulating wheel is returned again and the balls ground some more and meanwhile the feed plate is lifted, retracted over the balls and lowered for feeding again when a new cycle is begun.

I claim:

1. In a grinding machine having opposed wheels, a feed plate between the wheels, means for advancing the feed plate by two successive forward feeding strokes and retracting it by one stroke, and positive means for both lifting and lowering the feed plate between the end of the second feeding stroke and the beginning of a subsequent forward feeding stroke; substantially as described.

2. In a grinding machine having opposed wheels, a feed plate between the wheels, devices for controlling advance of the feed plate by two 150

- successive feeding strokes and a single retraction stroke, and toggle mechanism for lifting and lowering the feed plate; substantially as described. 80
3. In a grinding machine having opposed wheels, a feed plate, a slide having ways for slidably supporting the feed plate, means for moving the feed plate transversely of the slide, a cam, and adjustable actuating means between the cam and the slide; substantially as described. 85
- 10 4. In a grinding machine having opposed wheels, a feed plate, a slide having ways for slidably supporting the feed plate, a cam shaft having cams, means for actuating the slide from one of the cams and the feed plate from another, and 90 adjusting devices in said actuating means; substantially as described.
5. In a ball grinding machine having opposed wheels, a feed plate extending between the wheels and having a plurality of ball engaging teeth, 95 means for reciprocating the feed plate to advance the balls between the wheels, a feed block having an opening leading to the feed plate, a shutter plate for opening and closing the opening, a slide block for guiding the shutter plate across the 100 opening, and a sliding connection between the feed plate and the slide block; substantially as described.
6. In a ball grinding machine having opposed wheels, a feed plate extending between the wheels and having a plurality of ball engaging teeth, an inclined work support, a feed block having a ball opening leading to the inclined work support, the feed block having a lateral slot communicating with the opening, a shutter plate for opening or 105 closing the opening, and means for actuating the feed plate to carry a ball along the work support and through the lateral slot; substantially as described. 110
7. In a ball grinding machine having grooved 115
- 40
- wheels, a slidable support, ball feeding mechanism carried by the support, and mechanism for adjusting the support and feeding mechanism bodily lengthwise of the grooved wheels and crosswise of the grooves therein; substantially as described. 120
8. In a ball grinding machine having grooved wheels, a work support between the wheels, a slide for one of the wheels, a support transversely movable on the slide, ball feeding mechanism carried by the support, and mechanism for adjusting the support and the ball feeding mechanism transversely of the slide with respect to the wheels; substantially as described. 125
9. In a ball grinding machine having opposed wheels, a work support extending between the wheels, a feed plate extending over the work support, a feed block having an exit opening leading to the feed plate, means for actuating the feed plate to advance the balls along the work support from the exit opening, means for shifting the feed plate in another direction to clear the balls, and a shutter plate movable in the last direction with the feed plate to close the exit opening; substantially as described. 130
10. In a ball grinding machine having opposed wheels, a work support extending between the wheels, a feed plate extending over the work support, a feed block having an exit opening leading to the feed plate, means for actuating the feed plate to advance the balls along the work support from the exit opening, means for shifting the feed plate in another direction to clear the balls, a sliding block movable in the last direction with the feed plate, a shutter plate on the sliding block 135 to close the exit opening, and the sliding block having means to guide the feed plate in its first direction; substantially as described. 140
